DESIGN FOR A BEACH WEAR DRESS

Abraham M. Katz, Freeport, N. Y.

Application November 22, 1943, Serial No. 111,769

Term of patent 3½ years

To all whom it may concern:

Be it known that I, Abraham M. Katz, a citizen of the United States and a resident of the town of Freeport, in the county of Nassau and State of New York, have invented a new, original, and ornamental Design for a Beach Wear Dress, of which the following is a specification, reference being had to the accompanying drawing, forming a part thereof.

Fig. 1 is a front view of a beach wear dress showing my design, and
Fig. 2 is a rear view thereof.

I claim:

The ornamental design for a beach wear dress, substantially as shown.

ABRAHAM M. KATZ.
